SQUARE WITH TWO-PIECE HANDLE

Howard M. Peeples, Kingsland, Ga.

Application November 23, 1951, Serial No. 257,713

1 Claim. (Cl. 33—75)

1

This invention relates to a combined metal and wood handle for hand saws.

An object of this invention is to provide a combined metal and wood handle for hand saws wherein the grip portion is formed of wood and the metal portion supports and protects the wood grip.

Another object of this invention is to provide an improved metal and wood handle for hand saws wherein the metal portion of the handle is formed with a mitered edge and a square edge so that when the handle is mounted on a straight back saw the handle will form a tri-square, a framing square or a miter element.

A further object of this invention is to provide a saw handle which is simple in construction and can be produced at small cost for mounting on a conventional saw blade.

With the above and other objects in view, my invention consists in the arrangement, combination and details of construction disclosed in the drawings and specification, and then more particularly pointed out in the appended claim.

In the drawing:

Figure 1 is a detailed side elevation of a saw handle constructed according to an embodiment of this invention partly broken away and in section showing the handle mounted on a saw blade.

Figure 2 is a fragmentary plan view of the handle.

Figure 3 is a fragmentary sectional view taken on the line 3—3 of Figure 1.

Figure 4 is a fragmentary sectional view taken on the line 4—4 of Figure 1.

Figure 5 is a fragmentary vertical section of a modified form of this invention.

Referring to the drawing, the numeral 10 designates generally a hand saw blade which is provided with saw teeth 11 at its lower edge and is provided with a straight upper or back edge 12. A handle generally designated as 14 is mounted on the rear of the blade 10 and comprises a metal body 15 which is formed with a kerf or slot 16, within which the rear of the blade 10 is adapted to engage. The body 15 includes a pair of triangularly shaped plates 17 disposed on the opposite faces of the blade 10, and the latter is secured between the plates 17 by means of countersunk screws 18. The forward edge of each plate 17 is formed on a forty-five degree angle 19, and the rear of each plate 17 forms a right angular shoulder 20 which is disposed at a right angle to the back edge 12 of the blade 10.

In practice, the plates 17 are substantially thinner than the body 15 so as to thereby produce the right angular shoulder 20 which forms a square with the edge 12. The body 15 includes a rearwardly projecting arm 21 and a narrow or thin tongue 22. A hand grip 23 is adapted to be secured to the arm 21 and the tongue 22, the grip 23 being formed at its upper end with a slot or kerf 24 within which the tongue 22 is adapted to engage. The upper forward end of the grip 23 is secured to the tongue 22 by countersunk fastening means 25. The lower end of the grip 23 snugly engages on a flat upper side 26 formed on the arm 21, and a screw 27 extends through the arm 21 and is threaded into the lower end of the grip 23. The grip 23 is preferably formed of wood, and the screw 27, which has its head countersunk in the lower side of arm 21, is a wood screw.

Referring now to Figure 5, there is disclosed a modified form of securing the hand grip 23a to the arm 21a. A metal sleeve 28, which is externally threaded, is seated entirely within the lower end of the grip 23a being threaded into an opening provided therefor, and a machine screw 29 is extended through the arm 21a and is threaded into internal threads provided on the interior of the sleeve or socket 28. The forward side of the grip 23 forms with the rear side of the metal body 15 a hand hole or opening 30 within which the fingers of a hand may be freely extended.

In the use of this handle structure, the handle 14 is secured by the fastening means 18 to the rear of the blade 10. The upper edges 31 of the plates 17 are disposed either co-planar or parallel with the straight upper edge 12 of the blade 10. When the saw is being used for cutting wood, the handle may be grasped in the hand with the hand engaging about the grip 23. The arm 21, as shown in Figure 1, projects rearwardly from the lower end of the hand grip 23, as indicated at 32, so as to provide a metal protecting means beyond the grip 23 for protecting the latter in the event the saw is dropped.

The saw may be used for forming a miter by engaging the angled edge 19 on one edge of a board or the like, with the straight back edge 12 overlying the board. The saw may also be used for forming a right angle line by disposing a shoulder 20 against one edge of a board and positioning blade 10 on the upper side of the board. The right angle line may be drawn along the straight back or upper edge 12 of blade 10.

The handle hereinbefore described, which is made partly out of metal and partly out of wood, can be produced at a relatively small cost, and due to the combination of metal and wood, the handle will not readily become damaged or broken in the event the saw is dropped.

I do not mean to confine myself to the exact details of construction herein disclosed, but claim all variations falling within the purview of the appended claim.

What is claimed is:

In an elongated tool having a flat blade, a handle comprising a body including a pair of integral triangular plates engaging on opposite sides of said blade, one edge of each plate being disposed parallel with the adjacent edge of said blade, the forward edge of said body forming a shoulder extending from the outer side of each plate at right angles to said one edge, a rearwardly projecting arm extending from the lower end of said body, an integral tongue extending

rearwardly from the upper end of said body in a direction opposite to said plates, a grip member spaced from said body and formed with a slot in the upper end thereof within which said tongue engages, means securing said tongue in said slot, means extending through said arm securing the lower end of said grip member thereto, said arm projecting rearwardly from said grip and forming a seat and protecting means for said grip and a rest for the heel of a hand engaged about said grip.

HOWARD M. PEEPLES.
